US0D1088031S

(12) **United States Design Patent** (10) **Patent No.:** **US D1,088,031 S**
(45) **Date of Patent:** **** Aug. 12, 2025**

(54) **DISPLAY SCREEN OR PORTION THEREOF
WITH A GRAPHICAL USER INTERFACE**

(71) Applicant: **Meta Platforms, Inc.**, Menlo Park, CA (US)

(72) Inventors: **Alireza Jajarmikhayat**, San Francisco, CA (US); **Richard Harrington**, Los Angeles, CA (US); **Teemu Suviala**, Palo Alto, CA (US); **Marian Ming Chiao Cheung**, San Francisco, CA (US); **Zachary W. Stubenvoll**, Oakland, CA (US); **Samantha Kelsey Halle**, San Francisco, CA (US); **Andrew Alexander Stirk**, York (GB)

(73) Assignee: **Meta Platforms, Inc.**, Menlo Park, CA (US)

(**) Term: **15 Years**

(21) Appl. No.: **29/870,500**

(22) Filed: **Jan. 27, 2023**

Related U.S. Application Data

(63) Continuation of application No. 29/867,476, filed on Oct. 26, 2022, now Pat. No. Des. 981,450.

CLAIM

The ornamental design for a display screen or portion thereof with a graphical user interface, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

The FIGURE is a front view of a display screen or portion thereof with a graphical user interface.

The dashed broken lines depict portions of the graphical user interface that form no part of the claimed design. The dot-dashed broken lines depict the display screen or portions thereof that form no part of the claimed design.

1 Claim, 1 Drawing Sheet
